UNITED STATES PATENT OFFICE.

JOHN O. HICKS, OF LEVON, FLORIDA.

VEHICLE-AXLE.

1,267,221.

Specification of Letters Patent. Patented May 21, 1918.

Application filed May 8, 1914. Serial No. 836,715.

To all whom it may concern:

Be it known that I, JOHN O. HICKS, a citizen of the United States, residing at Levon, in the county of Marion and State of Florida, have invented new and useful Improvements in Vehicle-Axes, of which the following is a specification.

This invention is an improved axle adapted to be made of any suitable size and for use on carriages, wagons and other vehicles, the object of the invention being to provide an improved axle which comprises a main member and a pair of spindles detachably secured to the main member and so that the spindle members may be removed when desired.

The invention consists in the construction, combination and arrangement of devices hereinafter described and claimed.

20 In the accompanying drawings:—

Figure 1 is an elevation of an axle constructed in accordance with my invention.

Fig. 2 is a detail view of the same on a larger scale and with the clips shown in section.

Fig. 3 is a detail plan of one of the detachable members.

Fig. 4 is a bottom plan view of the main member.

25 The main member 1 of my improved axle is provided on its under side at its ends with rabbets 2 and with downwardly extending shoulders 3 on its under side and which form the inner ends of the rabbets. The outer sides of the shoulders are beveled inwardly and upwardly as shown at 4 in the same direction and at the same angle of inclination and the ends of the main member are correspondingly beveled as at 5. A 30 transverse groove 6 which is V-shaped cross sectionally extends across the under side of the member 1 near each end thereof and has one side wall formed with the same angle of inclination as the beveled end of the 35 rabbet.

Each detachable member 7 has a spindle 8, an arm 9 to fit in one of the rabbets 2 and a shoulder 10 to bear against one end of the member 1. Each shoulder 10 is undercut on its inner side by being provided with a bevel 11 and the inner end of each arm 9 is also beveled as at 12 to form an undercut for engagement with the beveled side 4 of the shoulder 3. On the opposite

side of each arm 9 is a transverse tongue 13 55 to enter one of the grooves 6 having one side wall formed with the same angle of inclination as the beveled portion on the end of the rabbet and to coöperate therewith in enabling the spindle to be connected 60 with the main member.

Grooves 14 are also provided in the upper side of the axle under the joints between the main member and the detachable spindle members. Clip bolts 15 have their 65 upper portions fitted in said grooves. Said clip bolts are arranged under the joints and coat with bars 16 and nuts 17 to securely and yet detachably fasten the spindle members to the ends of the main member 70 and permit their ready removal when this is desired. The interengaging projections 13 and grooves or recesses 6 prevent longitudinal slipping of the spindle members and the overhanging relation of the arms and 75 shoulders of the spindle members to the clipping portions of the main member also greatly increases the strength of the joints and causes only moderate stress to be imposed on the clips in binding the jointed 80 main and spindle members together. Said spindle member may be readily removed at slight cost if it should break and hence the axle can be kept in use for an indefinite length of time.

Having thus described my invention, I claim:—

The combination with an axle rabbeted at its end on its under side, the shoulder of the rabbet and extremity of the axle being 90 beveled inward and upward and the lower face of the axle over its rabbet having a longitudinal groove and a transverse groove of V-shape whose outer wall parallels said bevels; of a spindle, a stock carrying the 95 same and rabbeted on its upper side with its shoulder and extremity beveled to complete the bevels of the axle, tongues on its upper face to fit said grooves when the parts are assembled, and clips for holding the 100 parts together.

In testimony whereof I affix my signature in presence of two witnesses.

JOHN O. HICKS.
